Inventor

Julius Golon

UNITED STATES PATENT OFFICE.

JULIUS GOLON, OF SUFFIELD, CONNECTICUT.

TOBACCO-LEAF CONVEYER.

Application filed January 19, 1925. Serial No. 3,414.

To all whom it may concern:

Be it known that I, JULIUS GOLON, a citizen of the United States, and resident of Suffield, in the county of Hartford and 5 State of Connecticut, have invented a certain new and useful Tobacco-Leaf Conveyer, of which the following is a specification.

This invention relates to improvements in conveyers, particularly tobacco leaf 10 conveyers, and it is the principal object of the invention to provide a conveyer allowing a gradually lowering of a load, particularly tobacco leaf bunches from storage or curing lofts to transporting vehicles or the 15 like, and the automatic return of the conveyer cable after each operation.

Another object of the invention is the provision of a conveyer of simple and inexpensive construction adapted to be readily 20 attached and detached to and from a support.

A further object of the invention is the provision of a conveyer including a spring-controlled cable drum provided with means 25 for preventing a slipping or overlapping of the cable.

A still further object of the invention is the provision of a device of this type provided with a drum on which a suitable 30 length of cable is wound in two groups or series, the end of each having attached thereto the article engaging and carrying means.

These and other objects and advantages 35 of my invention will become more fully known as the description thereof proceeds, and will then be more particularly pointed out in the appended claim.

In the accompanying drawing, forming a 40 material part of this disclosure:

Figure 1 is a side elevation of a conveyer constructed according to my invention.

Figure 2 is a front view thereof, seen in the direction of the arrows 2-2 of Figure 45 1.

Figure 3 is a cross-section through the conveyer on line 3-3 of Figure 1.

The conveyer comprises a frame 10 including an upper cross-bar 11 equipped 50 with a hanger or hook 12 by means of which the device is suitably hung to one of the rafters or other support on a tobacco storing house or loft.

The frame is provided with suitable bearings 55 13 for a stationary shaft 14, carrying

within frame 10 a rotatable drum 15. Within this drum the inner end of a strong coil spring 16 is secured to the shaft 14, as at 17, and wound about the shaft in a plurality of convolutions, while the outer end of the spring is attached to the drum as indicated at 18.

A cable or rope of suitable material and length is wound upon the drum in two series or groups denominated 19 and 20 respectively, and to the outer ends of the cable, which are wound upon themselves to form eyes 21 and 22, are attached the upper ends of a hook-shaped carrier 23 connected by a cross-bar 24.

In order to prevent a shifting of the cable series or winding upon each other, the frame 10 intermediate its ends has cross-bars 25, and a slipping of the cables from or off the drum is prevented by hook-shaped members 26 secured at their inner ends as at 27 at both sides of the drum to one of the frame bars 10.

Suitable collars 28, 29 on shaft 14 prevent an undesirable displacement of frame 80 and drum.

The operation of the device is apparent from the above description. In use the hook 12 is hung over a rafter, and a bunch of tobacco leaves is attached to the hook-carrier 23. The strength of the spring is so selected that it will allow the drum to rotate under the proper weight to lower the load, and after the latter has been removed from the carrier, to automatically 90 wind the cable groups upon the drum for further use.

The guide-bars 25 will prevent a tangling of the cable and ensure at all times a proper winding of the same upon the drum, while 95 the hooks 26 will positively prevent the cable from slipping off the drum, so that the device will at all times properly operate and allow a ready lowering of the loads of tobacco leaves to the ground, and an automatic re-winding of the cable upon the drum after the removal of the load.

It will be clear that the device may be used for many other purposes too numerous to mention, and that changes may be made in the general arrangement and in the construction of the minor details without departure from the scope and spirit of the invention defined in the appended claim.

Having thus described my invention, what I claim as new and desire to secure by Letters Patent is:

In a tobacco leaf conveyer of the class 5 described, the combination of a shaft with a spring controlled drum revolving about said shaft, a cable wound about said drum in two groups spaced from each other, a unitary, hook-shaped article carrier held on 10 the ends of the cables of said groups, a

hanger for the conveyer, hook-shaped members attached at one end to said hanger and laterally engaging said cable groups, a means for keeping the cables in a single layer, and a means for preventing a displacement of hanger and drum.

Signed at Suffield, in the county of Hartford and State of Connecticut this 10th day of January A. D. 1925.

JULIUS GOLON.
